HOLDER FOR TUBE AND BOTTLE FEEDERS
FOR PETSDavid D. Lovitz, Short Hills, N.J., assignor to Sternco
Industries, Inc., Harrison, N.J., a corporation of New Jersey

Filed Aug. 21, 1969, Ser. No. 18,784

Term of patent 14 years

Int. Cl. D30—02
U.S. Cl. D30—13FIG. 1 is a perspective view of a holder for tube and bottle feeders for pets showing said new design as applied to a tube feeder and positioned within a terrarium.

FIG. 2 is a side view thereof, the opposite side view being identical.

FIG. 3 is a front view thereof.

FIG. 4 is a top view thereof.

FIG. 5 is a perspective view of said holder as applied to a bottle feeder and positioned within a cage.

The broken lines, representing tube and bottle feeders and fragmentary portions of the terrarium and cage operatively associated with said holder, are shown for illustrative purposes only.

I claim:

The ornamental design of a holder for tube and bottle feeders for pets, as shown and described.
